COMBINED LAVATORY, WATER CLOSET AND CABINET

James A. Tiller, Louisville, Ky., assignor to American
Radiator & Standard Sanitary Corporation, New York,
N.Y., a corporation of Delaware

Filed Aug. 8, 1961, Ser. No. 66,249

Term of patent 14 years

(Cl. D4—2)

The FIGURE is a view in perspective of a combined lavatory, water closet and cabinet.

The rear and side not shown are substantially plain. The side of the cabinet not shown is substantially identical to that shown, except as indicated. The side of the water closet not shown is substantially identical to that shown.

The side of the interior of the lavatory bowl not shown is substantially like the side shown.

The dominant features of the design reside in the portions shown in full line.

I claim:

The ornamental design for a combined lavatory, water closet and cabinet, substantially as shown and described.
